UNITED STATES PATENT OFFICE.

CLARENCE HENRY CHAMBERS, OF BROOKLYN, NEW YORK, ASSIGNEE OF ONE-HALF TO
MORRIS EICHENGREEN, OF NEW YORK, N. Y.

ENVELOP.

1,125,472.

Specification of Letters Patent.

Patented Jan. 19, 1915.

Application filed October 22, 1914. Serial No. 367,959.

To all whom it may concern:

Be it known that I, CLARENCE HENRY CHAMBERS, a citizen of the United States, residing in Brooklyn, county of Kings, 5 State of New York, have invented certain new and useful Improvements in Envelops; and I do hereby declare the following to be a full, clear, and exact description of the invention, such as will enable others skilled in 10 the art to which it appertains to make and use the same.

The invention relates to envelops which are intended to be sent through the mails unsealed, carrying circulars or the like; and 15 its object is to provide such an envelop which may be conveniently and fully opened for inspection, but which nevertheless securely retains its contents until so opened.

20 It is also an object of the invention to provide an envelop of this kind which has the appearance, the manner of handling and the fully gummed sealing flap of envelops intended for first-class mail matter.

25 In the accompanying drawing, in which is shown an illustrative embodiment of the invention, and in which the same reference numerals refer to similar parts in the several figures, Figure 1 is a plan view of the 30 blank from which the envelop is formed, and Fig. 2 is a plan view of a partly folded envelop.

Referring to the drawing, the blank from 35 which the envelop is formed consists of a body portion 1, a bottom flap 2, end flaps 3 and 4, and a sealing flap 5, the bottom flap being provided with a slit 6, for a purpose hereinafter described.

The free end 7 of one of the end flaps, as 40 3, is preferably shaped to form a tongue, and, in the illustrative embodiment of the invention shown, the other end flap 4 is provided with an adhesive, although it will of course be understood that the adhesive could 45 be placed on the upper surface of the end flap 3 instead of on the under surface of the end flap 4 without in any way departing from the spirit of the invention. The sealing flap 5 is provided with an adhesive 50 which may extend throughout the entire length thereof, if desired.

In forming the envelop, the bottom flap 2 is first folded down upon the body portion 1, after which the end flap 3 is folded 55 down upon the body portion and upon the

bottom flap, the free end 7 of the end flap being passed through the slit 6 in the bottom flap, whereby these two flaps are interlocked. The other end flap 4 is then folded down upon the end flap 3 and is permanently connected thereto by means of the adhesive, the free end of the flap 3 extending beyond the point of connection and beneath the end flap 4. 60

When the mailing matter is inserted in 65 the envelop, the sealing flap is folded down upon the end flaps and sealed thereto by means of the adhesive.

If inspection of the contents of the sealed envelop is desired, it is merely necessary to 70 insert the fingers in the envelop at the lower edge thereof, between the bottom flap 2 and the permanently connected end flaps 3 and 4, and then raise the end flaps from the bottom flap, thereby causing the withdrawal of 75 the free end 7 of the end flap 3 from the slit 6, and then withdraw the bottom flap.

What I claim is:

1. An envelop having a body portion, end flaps secured to one another, a bottom flap 80 extending between said body portion and said end flaps and detachably secured to one of said end flaps, and a sealing flap.

2. An envelop having a body portion, end flaps secured to one another, a bottom flap 85 extending between said body portion and said end flaps, said bottom flap and one of said end flaps being provided with co-acting interlocking means whereby said bottom flap is detachably secured to said one of said 90 end flaps, and a sealing flap.

3. An envelop having a body portion, an end flap, a second end flap overlapping said first-mentioned end flap and secured thereto, said first-mentioned end flap having a 95 free portion, a bottom flap extending between said body portion and said end flaps and having a slit through which the free portion of said first-mentioned end flap extends, and a sealing flap. 100

4. An envelop having a body portion, an end flap, a second end flap overlapping said first-mentioned end flap and secured thereto, said first-mentioned end flap having a free portion lying beneath said second-mentioned end flap, a bottom flap extending between said body portion and said end flaps and having a slit through which the free portion of said first-mentioned end flap extends, and a sealing flap. 105 110

5. An envelop having a body portion, an end flap, a second end flap overlapping said first-mentioned end flap and secured thereto, said first-mentioned end flap being provided with a tongue, a bottom flap extending between said body portion and said end flaps and having a slit through which said tongue extends, and a sealing flap.

In testimony whereof I affix my signature, in presence of two witnesses.

CLARENCE HENRY CHAMBERS.
